SKIRT HANGER

Leonard G. Kirkegaard, Denver, Colo., assignor to
 Leonard Hanger Co., Hollywood, Calif., a corporation of California

Application November 6, 1939, Serial No. 302,965

4 Claims. (Cl. 223—95)

This invention relates to a hanger for supporting ladies' skirts and has for its principal object the provision of a simple, light-weight device upon which the skirt can be quickly and easily placed; which will hold the skirt waist band in a smoothly stretched condition; which will freely suspend the skirt body to prevent wrinkling thereof; which can be actuated by a single hand; and which can be quickly and securely suspended from any suitable supporting medium.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a perspective view illustrating one form of the improved skirt hanger.

Fig. 2 is a longitudinal section thereof, taken on the line 2—2, Fig. 1.

Fig. 3 is an enlarged, fragmentary, cross section, taken on the line 3—3, Fig. 2.

Fig. 4 is a perspective view illustrating the improved hanger in place in a skirt band.

Fig. 5 is a perspective view of an alternate form of hanger.

Fig. 6 is a side elevation of the alternate form partially in section, the section being taken on the line 6—6, Fig. 5.

Fig. 7 is a perspective view illustrating the alternate form in place in a skirt.

The first form of the hanger employs a channelled frame member 10, the extremities of which are turned downwardly as shown at 11 and the body of which is provided with a longitudinally extending slot 12. A pair of slide members 13 and 14 project from the extremities of the frame member 10 through slotted openings in the downwardly turned extremities 11. The slide members are shaped to conform to and fit within the channel of the frame member 10.

The slide members are secured at their inward extremities to the extremities of a handle member formed from an inverted U-shaped, wire spring 15. The extremities of the spring 15 extend first downwardly through the slide members thence upwardly therethrough and terminate in overlying extremities 16 which overlie one edge of the slot 12 to support the inner ex-

tremities of the slide members 13 within the frame member 10. The natural resiliency of the spring 15 constantly urges both slide members outwardly in the frame member 10 to the full limits of the slot 12. An eye or loop 17 is formed at the mid portion of the spring member for holding a hanging hook 18 in position thereon.

The outer extremity of the slide member 13 is turned downwardly and shaped to form a single prong 19. The outer extremity of the slide member 14 is bifurcated and turned downwardly to form a pair of prongs 20. Rubber sleeves 21 are slipped over all of the prongs 19 and 20 to form frictional surfaces thereon.

In Fig. 4, the device is illustrated in position in a skirt waist band 22 of a skirt 23. It will be noted that the waist band 22 is folded over the single prong 19 and that the two extremities of the folded band are slipped over the pair of prongs 20 so that the spring 15 maintains the waist band taught in a four ply condition as illustrated.

The device can be quickly and easily inserted in, or removed from, place by simply squeezing or contracting the spring 15 in the palm of one hand while the other hand supports the skirt. The sleeves 21 assist in preventing the skirt from slipping from the prongs although the expansive action of the spring 15 is sufficient to hold the normal skirt without the sleeves if desired.

The alternate form of the invention, illustrated in Figs. 5, 6, and 7, employs the same principle of operation as the first form. It is designed, however, so that a plurality of skirts can be supported from a single supporting bracket.

The alternate form consists of a supporting rod 24 to the outer end of which a fitting 25 is secured. The fitting is preferably pressed from sheet metal and is formed with a pair of downwardly depending prongs 26. The other extremity of the rod is formed with an offset 27 which forms a stop for a second, slidable fitting 28. The second fitting is also preferably formed of sheet metal and is provided with a single downwardly depending prong 29.

A tubular spiral compression spring 30 surrounds the rod between the two fittings and acts to constantly urge them apart. The prongs 26 and 29 are preferably covered with rubber sleeves or tubes 31 as in the preceding form.

The rod 24 may be supported in any desired manner. One method of support is illustrated in Fig. 7, in which, a sheet metal bracket member 32 is employed. The bracket member 32 is formed with suitable ears 33 by means of which

it may be secured to a wall or other supporting surface. The upper face of the bracket member is provided with a series of perforations 34 for receiving a plurality of the rods 24.

5 As many rods can be inserted into the bracket member as desired. The offset extremities are simply inserted in the perforations and the offsets 27 allow the rods to overhang the edges of the bracket, as illustrated in Fig. 7, and limit the 10 horizontal arc of movement thereof.

To place a skirt upon the alternate form of the device a finger of each hand is inserted in the waist band and the latter is drawn taught behind the single prong 29. The single prong 29 15 is then pulled forwardly by drawing upon the band and the two loops in the skirt band are passed upwardly over the pair of prongs 26 and released to the position of Fig. 7. The skirt can be easily removed by simply drawing it forwardly 20 against the single prong and compressing the spring.

It will be noted that in both forms the skirt hangs in a straight natural position which will tend to remove wrinkles therefrom and which 25 will prevent the formation of additional wrinkles.

While a specific form of the improvement has been described and illustrated herein, it is desired to be understood that the same may be varied, within the scope of the appended claims, without 30 departing from the spirit of the invention.

Having thus described the invention, what is claimed and desired secured by Letters Patent is:

35 1. A skirt hanger comprising: an elongated frame member provided with an elongated longitudinal slot; downwardly turned extremities on said frame member; a slide member slidably supported at each extremity of said frame member and in alignment therewith; garment engaging means on each slide member; and an inverted U-shaped spring the extremities of which extend 40 downwardly through said slot into engagement

with said slide members to urge the latter apart.

2. A skirt hanger comprising: an elongated frame member provided with an elongated longitudinal slot; downwardly turned extremities on said frame member; a slide member slidably supported at each extremity of said frame member and in alignment therewith; garment engaging means on each slide member; an inverted U-shaped spring the extremities of which extend downwardly through said slot into engagement 10 with said slide members to urge the latter apart; and means for holding said slide member in slid-able engagement with said frame member.

3. A garment hanger comprising: a channel-shaped frame member having a longitudinally 15 extending slot; a downwardly turned extremity at each end of said frame member provided with an opening; a slide member at each extremity of said frame member, each of said slide members passing through one of said openings; and an 20 inverted, U-shaped wire spring having its ex-tremities extended downwardly through the elongated slot in the frame member, each of said ex-tremities being secured to one of said slide mem-bers.

4. A garment hanger comprising: a channel-shaped frame member having a longitudinally extending slot; a downwardly turned extremity at each end of said frame member provided with an opening; a slide member at each extremity of 30 said member, each of said slide members passing through one of said openings; and an inverted, U-shaped wire spring having its extremities ex-tended downwardly through the elongated slot in the frame member, each of said extremities being 35 secured to one of said slide members, said later extremities being passed upwardly so as to return-through said slot and being turned to over-lap said frame member to support the inner extremities of said slide member.
